TYPEWRITER

Richard Authier, Lausanne, Switzerland, assignor to
Paillard S.A., Sainte-Croix, Paud, Switzerland

Filed July 25, 1973, Ser. No. 382,549

Claims priority, application Switzerland Feb. 8, 1973

Term of patent 14 years

Int. Cl. D18—01

U.S. Cl. D64—11 A

FIG. 1.

FIG. 2.

FIG. 3.

FIG. 4.

FIG. 1 is a perspective view of a typewriter showing my new design, it being understood that the keys omitted for ease of illustration are continuous in the path indicated by the dot-dash lines in FIGS. 1 and 2;

FIG. 2 is a front elevational view;

FIG. 3 is a rear elevational view; and

FIG. 4 is a left side elevational view, the right side being a mirror image thereof.

I claim:

The ornamental design for a typewriter, substantially as shown and described.
